INVENTOR

Andrew M. Ernsberger,
BY A. M. Pierce,

ATTORNEY.

UNITED STATES PATENT OFFICE.

ANDREW M. ERNSBERGER, OF NEW YORK, N. Y.

CACHOU-HOLDER.

975,681.

Specification of Letters Patent. Patented Nov. 15, 1910.

Application filed April 5, 1909. Serial No. 487,869.

To all whom it may concern:

Be it known that I, ANDREW M. ERNSBERGER, a citizen of the United States, residing at New York, in the county of New York and State of New York, have invented certain new and useful Improvements in Cachou-Holders, of which the following is a specification, reference being had therein to the accompanying drawing.

10 My invention relates especially to receptacles or holders for cachous, pills or any article of a kindred nature which it is desired to deliver from the holder one at a time, and has for its object the provision of 15 a cheap, simple and effective device of this class.

To attain the desired end, my invention consists in certain novel and useful combinations or arrangements of parts and peculiarities of construction and operation, all of 20 which will be hereinafter first fully described and then pointed out in the claim.

In the drawing, Figure 1 is a plan view of a holder embodying my invention. Fig. 2 25 is a cross-sectional view at line *a—a* of Fig. 1. Fig. 3 is a plan view of the device with the rotatable top disk and eyelet removed.

Similar numerals of reference, wherever 30 they occur, indicate corresponding parts in all the figures.

1 is a body of any suitable material, preferably pasteboard, and 2 are cavities in said body.

3 is a bottom piece secured to the body 1. 35 4 is a disk or cover rotatably held to the body 1 by an eyelet 5.

6 is an ear or projection at the periphery of the disk 4.

7 is a perforation or opening in the disk.

8 represents cachous or pellets within the 40 cavities 2.

When constructed and arranged in accordance with the foregoing description, the operation of my device is as follows: Cachous or other pellets are placed within the 45 cavities, and the disk 4 turned so as to prevent the escape of a pellet. If it is desired to release one of the pellets, the disk is turned, by means of the ear 6, so as to cause the perforation 7 to register with one of the 50 cavities 2, thus permitting the escape of but one of the pellets, the others being held in place, and this manipulation may be continued at pleasure, insuring the delivery of but one pellet at a time, and this operation 55 may be accomplished while the device is held in one hand, the disk being moved by the thumb.

Having now fully described my invention what I claim as new therein, and desire to 60 secure by Letters Patent, is:

As an article of manufacture, a cachou holder in which is comprised a body portion provided with a receptacle for cachous, a disk secured to the back of said body, a movable disk having a perforation therein, and carrying a manipulating ear projecting beyond the periphery of the body, and an eyelet passing through the two disks and body, and on which the movable disk is rotatably 70 mounted.

In testimony whereof I hereto affix my signature in presence of two witnesses.

ANDREW M. ERNSBERGER.
